UNITED STATES PATENT OFFICE.

CLIFTON REEVES, OF TRENTON, NEW JERSEY, ASSIGNOR OF ONE-HALF TO
CHARLES HEATH, OF SAME PLACE.

COMPOUND LOCOMOTIVE-ENGINE.

SPECIFICATION forming part of Letters Patent No. 585,331, dated June 29, 1897.

Application filed April 20, 1896. Serial No. 588,401. (No model.)

To all whom it may concern:

Be it known that I, CLIFTON REEVES, a citizen of the United States of America, residing at Trenton, in the county of Mercer and State 5 of New Jersey, have invented certain new and useful Improvements in Compound Locomotive-Engines, of which the following is a specification, reference being had therein to the accompanying drawings.

10 My object is to produce a compound locomotive-engine provided with a valve so balanced and provided with such appliances as will result in an economy of steam, and consequently of fuel. I effect this economy by 15 providing an apparatus by which the steam after expansion in a high-pressure cylinder is transferred to a low-pressure cylinder, made, preferably, three and a half times larger than the high-pressure cylinder, in which low- 20 pressure cylinder the steam again performs an amount of work equal to the work performed by it in the high-pressure cylinder, thereby securing twice the work performed by an equal amount of steam under similar 25 conditions in a single-acting engine.

In my apparatus the steam is admitted into the high-pressure cylinder and from thence into the low-pressure cylinder and exhausted therefrom. This admission is by means of a 30 flat slide-valve which I have devised as an improvement over the round valve. This valve I arrange so that, while it is a slide-valve, it is completely balanced, the pressure underneath it equaling the pressure on the exposed

35 upper surface, thereby securing absence of friction from pressure and avoiding loss of power therefrom. I also provide easy and simple means of converting the engine into a single-acting engine at pleasure, securing a 40 continuance of the action of the engine should accident occur to the mechanism of the low-pressure cylinder. I also provide means by which a vacuum in the valve and in the low-pressure cylinder is prevented. I, further- 45 more, by the arrangement of the cranks connected with the engine, neutralize any twisting effect on the axles of the driving-wheel, and thereby by my arrangement of opposite cranks and connecting-rods I avoid the ham- 50 mer-blow on the track, caused in other engines by the presence of counterbalances in

the driving-wheels. I effect these objects by the mechanism hereinafter more fully described, and shown in the accompanying drawings.

In the drawings, Figure 1 is a side view in section of a portion of a locomotive-engine, showing in section the attachment of my mechanism thereto. Fig. 2 is an end view in half, showing in section the position of the 60 cylinders and steam chest and boiler. Fig. 3 is a view in section of the valve, steam-chest, valve-seat, and ports. Fig. 4 is a view in section of the relief-valve. Fig. 5 is a top view of another part of the same; and Fig. 6 65 is also a top view of the same, showing shape of the guides. Fig. 7 is a bottom view of another part of the same. Fig. 8 is a view in cross-section of balance-valve and steam-chest with starting-valve in place. Fig. 9 is 70 a bottom view of the balance slide-valve. Fig. 10 is a top view thereof. Fig. 11 is a side view thereof. Fig. 12 is a side view of valve with view in section of starting-valve. Figs. 13, 14, 15, and 16 show the starting-valve. 75 Fig. 13 shows the valve. Fig. 14 shows the end view of starting-valve. Fig. 15 shows side view of gate-valve, and Fig. 16 shows an end view of gate-valve. Fig. 17 is a front view of the driving-wheel with axle, cranks, 80 and attachments. Fig. 18 is a view in section of a part of the starting-valve, slide-valve, yoke, and steam-chest, showing attachment to the chest and location of the starting-valve.

85 A more particular description of this mechanism is as follows:

In Fig. 1, A is the balanced slide-valve. B is the high-pressure cylinder. B' is the low-pressure cylinder. C C are the high-pressure 90 ports. D D are the low-pressure ports. E is the exhaust-port. F F are faces of valve covering ports C C. G is the valve-stem. H is face covering exhaust-port E. B² is piston-head. B³ is piston-rod. B⁴ is forward cylinder-head of high-pressure cylinder, and B⁵ is rear cylinder-head of same. B⁶ is forward cylinder-head of low-pressure cylinder, and B⁷ rear cylinder-head of same. I is connecting-rod to axle. Back of this and hidden by 100 it is another connecting-rod to axle. W is the driving-wheel; Z, the rock-shaft arm; P²,

axle, and F⁷ a portion of the frame of the engine, and S⁵ is the saddle of the cylinders. The valves, valve-seats, ports, and attachments appear more clearly in Fig. 3, in the 5 description of which they will be more minutely enumerated.

In Fig. 2, B is the high-pressure cylinder; B', the low-pressure cylinder; S⁵, the cylinder-saddle; S⁶, the boiler; S, lid of steam-chest; F⁷, frame; O O, sides of steam-chest.

In Fig. 3, A A represent the slide-valve; C C, high-pressure ports; D D, low-pressure ports; E, exhaust-port; F F, faces of valve covering ports C C; F², outside lap of valve; F³, inside lap of valve; H, face of valve covering exhaust-port E; A', yoke of valve; G, valve-stem; L L, chambers over low-pressure ports; M M, openings leading to relief-valve; N N, packing-ring bearing against face T T; T T, 10 face of steam-chest cover; N³, cavity under packing-ring; O O, sides of steam-chest; P, opening for relief-valve; S, lid of steam-chest; K, screw to raise the gate-valve K'; Y Y, plate covering the gate-valve K'; D⁵ D⁶, screws to 15 fasten said plate; X' X', ports connecting cavities X⁵ X⁶ to equalize the pressure at both ends of the valve; J J, ports leading from the throttle; V, opening leading to cavity above the valve; V⁴, port connecting chambers L L. 20 M is opening leading to relief-valve. P and V are openings for relief-valves.

In Fig. 4, A A is a view in section of a part of the upper portion of the slide-valve, showing at M placed therein the relief-valve R. M⁴ M⁴ are guides to the valve bearing against side of opening M. R' are springs placed underneath R. C⁵ is a disk against which the spring bears. U is a cap perforated to admit air.

40 Fig. 5 is a bottom view of valve R, showing disk C⁵.

Fig. 6 shows top view of valve R and guides M⁴.

Fig. 7 is a bottom view of disk U, with perforations D⁸.

In Fig. 8, S is the lid of the steam-chest; A, the slide-valve; A², face of valve-seat; O O, sides of steam-chest. X' X' X' are ports leading from cavity X⁵ to X⁵ in Fig. 3. N is the packing-ring, bearing against face of steam-chest lid. N³ is the cavity underneath the packing-ring. In this cavity I place coil-springs which serve to keep the packing-ring against the face of steam-chest lid. As these 55 springs are not new in such connection I have not figured them. A' is the yoke of the valve, upon which rests the starting-valve and which is held in place by the lugs O' O', as shown in Fig. 18, which I preferably cast in one with 60 the side of the steam-chest.

In Fig. 9, L L represent a bottom view of the top of the chambers L L in Fig. 3, and U shows the bottom of the disk U of the relief-valve. There is one such valve to each 65 chamber.

In Fig. 10, which is a top view of the slide-valve, A A represents the portion of the valve

exposed to steam-pressure. N is the packing-ring, and N³ is a steam-tight joint in the ring. Y Y is a plate to strengthen the valve. K is the head of the screw for raising gate-valve, and M M are the openings to the relief-valve R. (Shown in Fig. 4.)

In Fig. 11, A shows the slide-valve. Openings A³ in the side lead to the chambers L L.

In Fig. 12, A A is another view of the side of sliding valve, showing attached thereto the starting-valve A⁵. The details of this starting-valve are shown more particularly in the 80 following figures.

In Fig. 13, A⁵ is the starting-valve with ports A⁶ and guides A⁷.

Fig. 14 is an end view of the starting-valve. A⁵ is the seat of the starting-valve.

In Fig. 15, C' is a rod for moving the starting-valve, and C² are lugs, through which the rod passes, attached to the starting-valve. Fig. 16 shows the end of this rod and lugs C².

In Fig. 17, R³ is the outside crank. 2 is the crank-pin. R⁴ is the pedestal-brace; R⁵, inside crank; R⁶, inside crank-pin; and E' E' are eccentrics.

Fig. 18 is a view showing the location of and method of holding the starting-valve in place within the steam-chest and against the 95 side of the slide-valve. This starting-valve rests upon the yoke A', and is kept from moving backward or forward by the lugs O' O', attached to the wall O of the steam-chest. It also shows the relative position of the ports 100 of the starting-valve and of the connecting-ports A³ of the slide-valve. When the slide-valve is not centered and the ports of the starting-valve are open, there is connection between the interior of the steam-chest and 105 either the front or rear chamber of the sliding valve by means of these ports, according as the slide-valve is in an advanced or retracted position. When the slide-valve is centered, there is no connection.

110 The operation of my mechanism is as follows: Steam being admitted from the boiler by the ports J J, it enters the cavities X⁵ X⁶, and by means of the ports X X, Fig. 3, and X' X', Fig. 8, the pressure in each of cavities 115 X⁵ is equalized and the slide-valve A is free to move backward and forward. The slide-valve moves forward and backward, as in other engines. A forward movement will uncover rear port C and admit steam from rear cavity X⁵ into rear port C and by that port into the rear end of high-pressure cylinder B. This movement also uncovers forward port C and releases the steam already used in the high-pressure cylinder, which thereby escapes 125 into forward chamber L. The gate-valve K' being closed, the steam thus released flows from this forward chamber L through forward port D to the low-pressure cylinder B'. By the same movement face H is carried forward 130 and uncovers or opens to rear chamber L the exhaust-port E, permitting the steam which has entered rear chamber L from the low-pressure cylinder by means of port D to es-

cape to the outer air. The forward movement of the valve having been completed, the backward movement as it progresses uncovers forward port C and permits the steam from 5 forward cavity X⁵ to enter the forward end of the high-pressure cylinder. The same movement also closes port E to rear port D and also uncovers rear port C, and the exhaust-steam from the rear end of the high-pressure cylinder by means of the rear port C and chamber L and rear port D enters the rear end of the low-pressure cylinder. It also uncovers or opens to forward chamber L the exhaust-port E, permitting the steam from 10 the forward end of low-pressure cylinder to escape by forward port D and forward chamber L to exhaust-port E. I thus operate the two cylinders by one slide-valve common to both. The outside lap of this valve is greater 15 than the inside lap, thereby permitting a cut-off earlier in the high than in the low pressure cylinder, thus economizing steam.

In case it be desired for any reason, such as accident or the like, to not use the low-pressure cylinder the gate-valve K' can be raised by means of the screw K, and the steam in the ports D being then free to pass through the gate-valve an equilibrium is established and the engine is run simply as a 20 high-pressure engine.

My relief-valves, as shown, are placed two of them in the body of the upper main portion of the slide-valve. They thus afford relief when a vacuum occurs in the chambers 25 L or either of them. If this vacuum occurs, the valve R is depressed by the outside pressure of the air and air flows into the vacuum through the openings M.

I have not figured the relief-valves at the 30 openings V and P, as they are to be found in use so placed in other engines.

As will be seen, the chambers L L about equal in area the exposed portion of the top of my slide-valve, and the pressure of the 35 exhaust-steam from the high-pressure cylinders upward against the upper parts of these chambers equals the pressure downward in the steam-chest upon the exposed parts of the top, thus affording a slide-valve balanced.

50 The advantages of my construction, among others, are:

I have a slide-valve avoiding pressure and consequent friction.

I operate two cylinders by one valve, the 55 ports always remaining in relative adjustment, dispensing with an extra valve, with its separate adjustments, and permitting a diminution of weight, material, machinery, cost of production, friction, wear, and other 60 causes of expenditure.

I also produce an engine which can at pleasure, with but a few moments loss of time and with no destruction of the parts, be converted from compound to single, and vice versa.

65 By placing relief-valves in the body of the slide-valve I avoid a vacuum underneath the valve and in the low-pressure cylinder, avoid-

ing the drawing in of cinder through the exhaust, which would cut the faces of the valve and the cylinder, and permitting a free steady 70 run to the engine upon the closing of the throttle.

What I claim as my invention, and desire to secure by Letters Patent, is—

1. A steam-engine comprising a steam-chest 75 having ports, high and low pressure cylinders provided with pistons, a balance slide-valve in said steam-chest, having a gate therein and ports and adapted to control the admission of steam to the rear end of the high-pressure cylinder, simultaneously with the admission of steam to the forward end of the low-pressure cylinder, the exhaust of steam from the high-pressure cylinder to the end of the low-pressure cylinder adjacent thereto, the exhaust of 80 used steam from said low-pressure cylinder, and conversely, when the gate is closed, and when open to control the admission of steam to the rear end of the high-pressure cylinder and the exhaust of steam therefrom and conversely, substantially as described. 85

2. A steam-engine having a steam-chest provided with ports, high and low pressure cylinders provided with pistons, and a balance slide-valve in said steam-chest provided 95 with a gate therein and ports, and valve-faces, said valve-faces adapted to control the admission and exhaust of steam to and from the high and low pressure cylinders and the slide-valve and the exhaust of used steam 100 therefrom when said gate is closed, and when open, to permit the escape of the steam direct from the high-pressure cylinder into the slide-valve and the exhaust of the used steam 105 therefrom, substantially as shown and described.

3. A steam-engine having a steam-chest provided with ports, high and low pressure cylinders provided with pistons, and a balance slide-valve in said steam-chest provided 110 with chambers having ports leading therefrom, a port connecting said chambers, a gate therein adapted to open and close this port, and valve-faces, said valve-faces adapted to control the admission and exhaust of the 115 steam to and from the high and low pressure cylinders and the slide-valve when said gate is closed and when open to permit the escape of the steam direct from the high-pressure cylinder into the slide-valve and the exhaust of 120 used steam therefrom, substantially as shown and described.

4. A steam-engine having a steam-chest provided with ports, high and low pressure cylinders, provided with pistons and a balance slide-valve located in said steam-chest having chambers provided with ports opening therefrom, a port connecting said chambers, and a gate adapted to open and close said port, substantially as shown and described. 125

5. A steam-engine having a steam-chest provided with a valve-seat, and high and low pressure cylinders provided with pistons, said valve-seat having one set of ports leading to 130

- and from the high-pressure cylinder, and another set of ports leading to and from the low-pressure cylinder, and also having an exhaust-port, in combination with a slide-valve 5 having a gate therein and provided with valve-faces arranged relatively to said ports so that when the front port leading to the high-pressure cylinder is open to the steam-chest, the rear port of the same cylinder will 10 be uncovered to connect with the rear port of the low-pressure cylinder, and the forward port of the low-pressure cylinder will be open to connect with the exhaust-port, substantially as shown and described.
- 15 6. A steam-engine chest provided with a valve-seat having one set of ports leading to and from a high-pressure cylinder, and another set of ports leading to and from a low-pressure cylinder, and also having an exhaust-port, in combination with a slide-valve having chambers connected by a port provided with a gate capable of being raised or lowered and thereby opening or closing said port, such slide-valve provided with valve-faces arranged relatively to said ports so that when the front port leading to the high-pressure cylinder is open to the steam-chest the rear port of the same cylinder will be uncovered to connect by means of the rear of said 20 chambers with the rear port of the low-pressure cylinder, and the forward port of the low-pressure cylinder will be open to connect by means of the forward one of said chambers with the exhaust-port, substantially as 25 shown and described.
- 30 7. In a steam-engine a steam-chest provided with one set of ports leading to and from a high-pressure cylinder, and another set of ports leading to and from a low-pressure cylinder, and also provided with an exhaust-port, in combination with a slide-valve having chambers connected by a port having a gate adapted to close or open the same, such slide-valve provided with valve-faces arranged relatively to said ports so that when the front port leading to the high-pressure cylinder is open to the steam-chest the rear port of same cylinder will be open to connect by means of the rear chamber with the rear 35 port of the low-pressure cylinder and the forward port of the low-pressure cylinder will be open to connect by means of the forward chamber with the exhaust-port, and when the port between said chambers is open by means of the raising of said gate the rear port of the high-pressure cylinder will be open to connect by means of said chambers with the exhaust-port, substantially as shown and described.
- 40 8. In a steam-engine, a steam-chest provided with a valve-seat having one set of ports leading to and from a high-pressure cylinder, and another set of ports leading to and from a low-pressure cylinder, and also having an exhaust-port, in combination with a slide-valve having chambers connected by a port

a gate therein adapted to open and close said port, such slide-valve having faces arranged relatively to said ports so that when the port leading to the high-pressure cylinder is open to the steam-chest and the exhaust-port, the rear port of the same cylinder will be uncovered to connect by means of the rear chamber the port connecting said chamber and the front chamber to the exhaust-port, substantially as shown and described.

9. A steam-engine having a steam-chest provided with ports, high and low pressure cylinders provided with pistons connected respectively by suitable means to opposite cranks of one common axle, a balance slide-valve in said steam-chest provided with chambers having ports leading to and from said cylinders, a port connecting said chambers, a gate adapted to open and close said port, and valve-faces adapted to control the admission and exhaust of the steam to and from the high and low pressure cylinders and the slide-valve when said gate is closed, and when open to permit the escape of the steam direct from the high-pressure cylinder into the slide-valve and the exhaust of used steam therefrom, substantially as shown and described.

10. A steam-engine having high and low pressure cylinders provided respectively with pistons connected, each, by suitable means to opposite cranks of one common axle, such engine provided with a steam-chest having a valve-seat with one set of ports leading to and from the high-pressure cylinder, and another set of ports leading to and from the low-pressure cylinder, and also having an exhaust-port, in combination with a slide-valve having chambers connected by a port capable of being opened or closed by a gate and provided with such gate and means for opening and closing the same, and having faces arranged relatively to the ports leading to and from the cylinders so that when the port connecting the chambers is open, the steam is free to exhaust from the high-pressure cylinder by means of the chambers to the exhaust-port, and when the port connecting the chambers is closed the steam from the high-pressure cylinder is forced to enter the port leading to the low-pressure cylinder, all arranged substantially as shown and described.

11. In a steam-engine a steam-chest having ports and provided with a starting-valve and a slide-valve also provided with ports, said slide-valve having interior chambers, connected by a port capable of being opened or closed by a gate, the ports A³ of the slide-valve arranged relatively to the ports of the starting-valve, whereby when the slide-valve is off of center and the starting-valve is open, communication is established by means of the ports A³ of the slide-valve and the ports of the starting-valve between the interior of the steam-chest and the forward interior chamber of the slide-valve when such slide-valve is advanced, and between the interior of the

steam-chest and the rear chamber of the slide-valve, when such slide-valve is retracted, substantially as shown and described.

12. In a steam-engine, a steam-chest having ports provided with a starting-valve also having ports, and held in place by lugs attached to the interior wall of the steam-chest, and a slide-valve having interior chambers connected by a port capable of being opened or closed by a gate and also provided with ports A³, arranged relatively to the ports of the starting-valve, whereby when the slide-valve is off of center and the starting-valve is open, communication is established by means of the ports A³, of the slide-valve, and the ports of the starting-valve between the interior of the steam-chest and the forward interior chamber of the slide-valve when such slide-valve is advanced, and between the interior of the steam-chest and the rear chamber of the slide-valve when such slide-valve is retracted, substantially as shown and described.

13. A steam-engine having a steam-chest provided with ports, high and low pressure cylinders provided with pistons connected respectively by suitable means to opposite cranks of one common axle, a balance slide-valve in said steam-chest provided with chambers having ports leading to and from said cylinders, a port connecting said chambers, a gate adapted to open and close said port, and valve-faces adapted to control the admission and exhaust of the steam to and from the high and low pressure cylinders into the slide-valve when said gate is closed, and when open to permit the escape of the steam direct from the high-pressure cylinder into the slide-valve and the exhaust of used steam therefrom, in combination with a starting-valve having ports arranged relatively to the ports A³, of the slide-valve, so that when the slide-valve is off of center, and the starting-valve is open, communication is established, by means of the ports of the starting-valve and the said ports of the slide-valve, between the interior of the steam-chest and the forward chamber of the slide-valve, when such slide-valve is advanced, and between the interior of the steam-chest and the rear chamber of the slide-valve when the slide-valve is retracted, substantially as shown and described.

14. A steam-engine having a steam-chest

provided with ports, high and low pressure cylinders provided with pistons connected respectively, by suitable means, to opposite cranks of one common axle, a balance slide-valve in said steam-chest provided with chambers having ports leading to and from said cylinders, a port connecting said chambers, a gate adapted to open and close said port, and valve-faces adapted to control the admission and exhaust of the steam to and from the high and low pressure cylinders and the slide-valve when said gate is closed, and when open to permit the escape of the steam direct from the high-pressure cylinder into the slide-valve and the exhaust of used steam therefrom, in combination with a starting-valve held in place by lugs attached to the interior wall of the steam-chest, such starting-valve ports arranged relatively to the ports A³, of the slide-valve, so that when the slide-valve is off of center, and the starting-valve is open, communication is established by means of the ports of the starting-valve and the said ports of the slide-valve between the interior of the steam-chest and the forward chamber of the slide-valve when such slide-valve is advanced, and between the interior of the steam-chest and the rear chamber of the slide-valve when the slide-valve is retracted, substantially as shown and described.

15. An engine, consisting of high and low pressure cylinders, a steam-chest having ports connecting the said cylinders and a slide-valve in said steam-chest provided with a chamber having a gate located therein moving therewith, adapted to be held in an open or closed position, substantially as described.

16. An engine, consisting of high and low pressure cylinders, a steam-chest having ports connecting the said cylinders, a slide-valve in said steam-chest provided with a chamber having a gate located therein moving therewith, adapted to be held in an open or closed position, and a starting-valve, said valve adapted to coöperate to start the engine substantially as described.

In testimony whereof I have affixed my signature in presence of two witnesses.

CLIFTON REEVES.
